UNITED STATES PATENT OFFICE.

EDWARD WOLLET, OF CLEVELAND, OHIO.

HORSESHOE.

No. 879,936.

Specification of Letters Patent.

Patented Feb. 25, 1908.

Application filed February 18, 1907. Serial No. 358,022.

To all whom it may concern:

Be it known that I, EDWARD WOLLET, a citizen of the United States, residing at Cleveland, in the county of Cuyahoga and State of Ohio, have invented new and useful Improvements in Horseshoes, of which the following is a specification.

My invention is an improved horseshoe having detachable calks which may be readily removed and replaced by others when they have become worn, and may be also removed and replaced by calks appropriate to different conditions; and the said invention consists in the construction, combination and arrangement of devices hereinafter described and claimed.

In the accompanying drawings,—Figure 1 is a top plan view of a horse shoe constructed in accordance with my invention; Fig. 2 is a sectional view of the same taken on the plane indicated by the line *a—a* of Fig. 1; Fig. 3 is a front elevation of the same; Fig. 4 is a detail perspective view of one of the calks; Fig. 5 is a detail bottom plan view of one of the heel portions of the shoe and of a modified form of heel calk.

In accordance with my invention, the horse shoe 1, which may be of any suitable shape and construction, is provided with elongated slots for the reception of key flanges on the upper ends or faces of the detachable calks. Slots 2 for the reception of the key flanges 3 of the toe calks 4 are obliquely disposed in the toe portion of the shoe and each of the said slots has one end inclined downwardly to be engaged by the correspondingly inclined end 5 of the key flange 3. The key flange of each toe calk is obliquely disposed on the upper face of the calk and projects at one end at 3^a beyond the side of said calk, and when the said flange is in the appropriate slot 2, the outer rear end of said key flange is engaged by the threads of a screw 6, which screw also engages a vertical threaded opening 7 in the shoe. The head of the screw 6 bears on the under face of the projecting end 3^a of the key-flange 3 and on the shoe which in conjunction with the co-acting inclined ends of the slot and key holds the calk against downward movement; hence the screws perform the double function of holding the calks against vertical and lateral movement. It will be understood that the shoulders formed by the ends of the upper surfaces of the toe calks on either side of the key-flanges bear under the shoe and that

the screws 6 coact with the key flanges and key slots to secure the calks firmly to the shoe and yet enable said calks to be readily removed from the shoe, it being only necessary to first remove the screws 6 to permit the key flanges to be moved longitudinally in the key slots to clear the inclined ends of said flanges from those of said slots and hence enable said key flanges to be readily taken out from the under sides of said slots without the necessity of having to first remove the shoe from the horse's hoof.

Within the scope of my invention the toe calks may be of any shape and construction. They are here shown for the purpose of this specification as beveled edge calks, such as are adapted for use on icy roads and streets.

The key slots 8 in the heel portions of the shoe are precisely similar to the slots 2 in the toe portion thereof, excepting that they are substantially parallel with the sides of said heel portions. The heel calks 9 have key flanges 10 to enter said slots 8 and the ends 8^a project beyond the sides of the calks and are engaged by the screws 13 in the same manner as are the toe calks. Each of said slots has one end inclined, as at 11, and each of said key flanges has one end inclined, as at 12, to engage said inclined end of said slot. A screw 13 coacts with the shoe and with each of said key flanges to secure said heel calks detachably in place. The heel calks may also within the scope of my invention be of any suitable construction. As indicated in Figs. 1 and 2 the heel calks have oppositely beveled, downwardly converging front and rear sides. In the modification shown in Fig. 5, the heel calk 14 has oppositely beveled, lateral surfaces. I do not limit myself in this particular.

From the foregoing description, taken in connection with the accompanying drawings, the construction and operation of the invention will be readily understood without requiring a more extended explanation.

Various changes in the form, proportion and the minor details of construction may be resorted to without departing from the principle or sacrificing any of the advantages of the invention, as defined by the appended claim.

Having thus described my invention, what I claim as new and desire to secure by Letters-Patent, is:

In combination with a horseshoe having a key slot extending therethrough, one end of

said slot being inclined and the other end screw-threaded, of a calk having a key flange extending transversely across the base thereof intermediately of its ends and projecting at opposite ends beyond the sides of said calk, one end of said flange being inclined to engage the inclined end wall of said slot and the other end screw-threaded to coact with the screw-threaded end of said slot to form a screw-receiving aperture, and a set-screw to

engage said screw-threaded portion of said slot and flange to wedge and hold said flange tightly in position.

In testimony whereof I have hereunto set my hand in the presence of two subscribing 15 witnesses.

EDWARD WOLLET.
